UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR.

Application filed September 5, 1919. Serial No. 321,838.

To all whom it may concern:

Be it known that I, ARTHUR O. AUSTIN, a citizen of the United States, residing at Barberton, in the county of Summit and 6 State of Ohio, have invented certain new and useful Improvements in Insulators, of which the following is a specification.

This invention relates to insulators and similar structures and has for its object the 10 provision of a device of the class named which shall include resilient connection between the parts and which shall be of improved construction and operation.

The invention is exemplified in the combination and arrangement of parts shown in the accompanying drawings and described in the following specification, and it is more particularly pointed out in the appended claims.

20 In the drawing—

Fig. 1 is a central sectional view of an insulator showing one embodiment of the present invention.

Fig. 2 is a sectional view of the insulator 25 pin showing a modified form of the invention.

Figs. 3 and 4 each illustrates another modification of the invention.

Fig. 5 is an elevation partly in section 30 showing a different form of the invention.

Fig. 6 is a fragmentary section showing a locking arrangement for a resilient member illustrated in Fig. 5.

In my prior Patents No. 1,284,976, dated 35 November 19, 1918, and No. 1,291,713, dated January 21, 1919, I have shown an insulator provided with means cooperating with the cement to provide resilient connection between the parts. The present invention includes certain improvements over the device shown in my prior patents.

In Fig. 1 of the drawings the numeral 10 designates the dielectric member of an insulator supported by a cap 11 and provided 45 with a pin 12 for carrying the loads suspended by the insulator. The pin 12 is provided with a plurality of circumferential flanges 13 which are longitudinally spaced on the pin and which afford a relatively resilient connection between the pin and the dielectric member, or cement, or holding medium. The flanges 13 on pin 12 are enclosed in a thin sheet metal thimble or sleeve 14 which is preferably grooved

circumferentially as shown at 14', the 55 grooves being arranged to extend inwardly between the flanges 13. The sleeve 14 may be integral or formed in parts held in place by the cement or other means. The sleeve 14 bears upon the flanges 13 adjacent their 60 peripheries but preferably a slight clearance is permitted between the very outermost portions of the flanges and the sleeve 14 as shown at 15. This causes the sleeve to bear upon each flange on each side thereof adjacent the outer periphery so that slight movement of the sleeve is permitted in a radial direction relative to the pin 12. The outer face of the sleeve 14 is connected to the dielectric member 10 by interposed cement 70 75 16 in a manner similar to that shown in my prior patents referred to above. It will be apparent, however, that in no place is there an absolutely unyielding bearing between the pin and the cement. The corrugated sleeve 14 will give under pressure at any point unless it is backed by an unyielding support, and since the sleeve bears only on the sides of the yielding flanges 13, there is no point where the sleeve is unyieldingly backed. This yielding connection between the pin and the dielectric member not only lessens the danger of cracking from uneven expansion and contraction due to temperature changes, but also effects a 80 85 distribution of stresses in the dielectric member which greatly reduces the dangerous effect of such stresses.

It will be noted that the flanges 13 vary in thickness and spacing upon the pin 12 90 and this variation in the flanges is for the purpose of securing a graduation in the stress transmitted from the pin to the fragile portion of the insulator. It will be readily apparent that the stiffer flanges will 95 transmit a greater portion of the stress from the pin to the fragile member and that where the flanges are arranged more closely together a greater portion of the stress will be transmitted than at points where the flanges are more widely distributed. In the arrangement shown in the drawings, the stress transmitted to the fragile portion of the insulator will be greatest adjacent the central portion of the flanged pin and will gradually decrease toward the ends of the flanged portion. This arrangement is found to be effective in reducing the 100 105

dangerous stresses, such as shearing and tension, and consequently greatly to increase the load which may be safely carried by an insulator of a given size.

- 6 It will be apparent that the same arrangement which is applied to the pin is also applicable to the connection between the cap and the dielectric member. This is illustrated by a sheet metal corrugated 10 ring 17 carried by flanges 18 extending inwardly from the inner face of the cap 11, the ring 17 being secured to the dielectric member by cement interposed between the two parts and shown at 19.
- 14 In the figure just described the space between the metal sleeve and the flanged support which carries the sleeve is left open, being filled only with air. It may be desirable in some cases to have this space occupied 20 by some form of yielding material, and in Fig. 3 a pin 12 similar to that shown in Fig. 1 is represented as provided with a sleeve 14 and the space between the pin and sleeve is filled with yielding material 20.
- 24 This material may be a resilient substance such as a weak cellular cement or rubber, which will spring back when compressed, and give some support to thin walls of the shell or thimble, or it may be an easily 30 yielding non-resilient material such as lead, which will be permanently deformed by compression and thus accommodate the shape of the backing for the sleeve 14 to the requirements of a particular installation.

It is apparent that the form of the sleeve 14 may be considerably varied and that the points of connection between the sleeve and the flanges 13 may also be changed. In the 40 form of the invention shown in Fig. 2 the corrugations of the sleeve 14 instead of extending inwardly between the flanges 13 project outwardly and the sleeve is provided with slight grooves 21 which are supported upon the peripheries of the flanges 13.

In the form of the invention shown in Fig. 4 an inner sleeve 22 is carried by flanges 23 of the pin 12 in a manner similar to that shown in Fig. 1, but in this case the flanges 23 are represented as arranged to form the threads of a screw and the sleeve 22 may bear directly on the peripheries of the flanges. The corrugations of the sleeve 55 will conform to the threaded arrangement of the flanges 23 so that the sleeve may be screwed into place on the pin. A second or outer sleeve 24 is provided with corrugations of threaded form so that the outer 60 sleeve may be threaded into engagement with the outer face of the inner sleeve. The corrugations in the outer sleeve are deeper than those of the inner sleeve so that the two sleeves bear upon one another only at points intermediate the flanges 23. It will be ap-

parent that by this arrangement there is no part of the outer sleeve which is provided with an absolutely fixed or rigid backing so that all portions of the outer sleeve are free to yield to pressure exerted against it. 70 The dielectric member 25 in this case is provided with threaded grooves into which the outer sleeve 24 may be threaded directly without the necessity of the interposition of cement. 75

In the form of the invention shown in Fig. 5, the insulator is provided with a cap 25 which may be of pressed sheet steel as illustrated in the drawing. A dielectric member 26 is connected with said cap and is provided with a sanded surface 27 such as is described in my prior Patent No. 1,284,975, dated November 19, 1918. Interposed between the cap 25 and insulator 26 is a cup-shaped member of relatively thin 80 resilient sheet metal 28. The member 28 is provided with peripheral corrugations 29 which may be arranged in the form of a helical screw, as shown in the figure. The wall of the cap 25 has a plurality of tongues 30 punched inwardly and arranged in the form of a helix of the same pitch as the screw formed by the corrugations 29. It will be apparent that the cup 28 may be threaded into the interior of the cap 25 and that the tongues 30 will provide resilient supports for the corrugations on the cup. Cement 31 or other connecting material is interposed between the inner face of the cup 28 and the sanded surface 27 for securing 90 the dielectric member 26 to the resilient cup 28. The entire structure thus formed may be threaded into the cap 25 thus providing a detachable connection between the insulator and the cap. The cap 25 may be provided with one or more tongues 32, as illustrated in Fig. 6, which can be bent into depressions in the lower corrugation on the cup 28 to lock the two parts together. If, at any time, it is desirable to separate the 100 parts, as in case of failure of one of the parts, the tongues 32 may be sprung outwardly by a pair of pliers or other suitable tool and the parts unscrewed from one another. Since the member 28 which bears 110 against the cement 31 is resilient throughout, and since it is resiliently supported on the cap 25 by the tongues 30, it is apparent that the entire bearing between the cap 25 and the cement will permit of yielding at 120 any point, thus preventing concentration of stresses at any given position in the cement.

The pin 12 in the interior of the dielectric member is provided with resilient flanges 33 which may be arranged at an angle to the pin 12 and which are formed in the shape of threads of a helical screw. An envelop or thimble 34 of resilient sheet material is provided with peripheral corrugations 35 which constitute the threads of a 130

helical screw of a pitch corresponding to that of the flanges 33. The thimble 34 is threaded over the pin 12 and is then connected with the dielectric member 26 by cement 36. Any suitable form of lock may be provided for holding the parts 12 and 34 from unscrewing under load, or the parts may fit sufficiently tight to resist tendency to separate in this manner. The sheet metal 10 thimble 34 provides a resilient member for engaging the cement 36 and this member is supported from the pin 12 by resilient projections so that every point of contact between the pin and the cement is capable of 15 yielding under stress. The arrangement also provides a detachable connection between the parts.

If the metallic parts of an insulator are provided with projecting points or thin ribs 20 for providing resilient connection with the dielectric member, they have a tendency to concentrate the electrostatic flux which may damage the dielectric or holding medium. A covering or envelop of sheet metal over 25 these projections, as provided by this invention, overcomes this difficulty and gives a practically uniform flux distribution. This feature is especially valuable in high frequency, high potential installations, such as 30 are used in wireless work.

I claim:

1. An insulator, comprising a plurality of parts, and means for connecting said parts to one another, comprising a yielding member 25 for engaging one of said parts and yielding means for connecting said member to the other of said parts comprising yielding spacers having contact with said yielding member only at spaced points distributed 40 thereon, said yielding member being secured to said spacers to transmit the load on said insulator from one of said parts to the other through said spacers and yielding member.

2. An insulator, comprising a plurality of 45 parts, a yielding member of sheet material for engaging one of said parts, and yielding spacers for connecting said member with the other of said parts said spacers having contact with said sheet member only at 50 spaced points thereon to support said sheet member in spaced relation with the last-mentioned part, said yielding member being secured to said spacers to transmit the load on said insulator from one of said parts 55 to the other through said spacers and yielding member.

3. An insulator, comprising a plurality of parts, a sheet metal sleeve engaging one of said parts, and means for yieldingly connecting said sleeve with another of said parts, said connecting means having yielding contact with said sleeve at spaced intervals thereon and supporting the intervening portions of said sleeve free from direct supporting bearing.

4. An insulator, comprising a member having resilient projections thereon, and a resilient member of sheet material supported by said projections and having contact therewith at yielding portions only 70 thereof while portions of said sheet material intermediate the contacting portions are free from supporting contact.

5. An insulator, comprising a connecting member having resiliently flexible projections thereon, a resilient member of sheet material supported at spaced intervals by said projections and in spaced relation with said connecting member and a dielectric member connected with said member of sheet 80 material.

6. An insulator, comprising a metallic supporting member having resiliently flexible projections thereon, a resilient sheet metal sleeve carried by a plurality of said 85 projections, and a dielectric member connected with said sleeve.

7. An insulator, comprising a metallic supporting member having spaced resilient projections thereon, a sleeve of resilient corrugated sheet metal carried by said projections, and contacting with said projections adjacent the extremities only thereof, and a dielectric member secured to said supporting member by said sleeve and projections.

8. An insulator, comprising a supporting member and a dielectric member, and means for transmitting stress in the direction of the load on said insulator from one of said 100 members to the other comprising a resilient member engaging said dielectric member and spaced resiliently flexible projections on said supporting member and engaging said resilient member and secured thereto against 105 movement in the direction of the load.

9. An insulator, comprising a dielectric member, a member composed of yielding sheet material connected with said dielectric member, a support for said dielectric member, and projections on said support for connecting said member of sheet material with said support, said sheet material member being carried on flexible yielding extremities of said projections to permit yielding at all 115 points where projections contact with said member of sheet material and to leave other portions of said sheet material free from supporting contact.

10. An insulator, comprising a supporting 120 member having yielding projections thereon, said projections having different degrees of resiliency at different points on said supporting member, a dielectric member carried by said supporting member, and a member 125 of yielding sheet material interposed between said projections and said dielectric member.

11. An insulator, comprising a supporting member having yielding projections un- 130

- equally spaced thereon, a dielectric member connected with said supporting member, and a member of yielding sheet material interposed between said projections and said dielectric member for connecting said supporting member with said dielectric member.
12. An insulator, comprising a supporting member having a plurality of unequally spaced resilient projections thereon, said 10 projections having different degrees of resiliency at different positions on said supporting member, a dielectric member connected with said supporting member, and a member of yielding sheet material interposed between said projections and said dielectric member for connecting said dielectric member with said supporting member.
13. An insulator, comprising a metallic member having resilient projections unequally spaced thereon and arranged to afford different degrees of resiliency at different positions on said supporting member, a dielectric member connected with said supporting member, and a sleeve of resilient 25 sheet material interposed between said dielectric member and said projections for transmitting stresses between said projections and said dielectric member.
14. An insulator, comprising a supporting member having a plurality of resilient flanges thereon, a dielectric member connected with said supporting member, and a corrugated resilient sleeve interposed between said flanges and said dielectric member.
15. An insulator comprising a metallic part and a dielectric member, said metallic part having spaced resilient projections thereon for transmitting mechanical stress 40 to said dielectric member, and an envelope of conducting material interposed between said projections and said dielectric member and spaced from said metallic part intermediate said projections.
16. An insulator comprising a metallic part and an insulating member, said metallic part having resilient projections thereon for transmitting mechanical stress to said dielectric member, and an envelope of resilient 50 sheet metal interposed between said projections and said insulating member for affording resilient bearing on said insulating member and for controlling the distribution of electrostatic flux in said insulating member, said envelope being spaced from said metallic part intermediate said projections.
17. An insulator comprising a pair of members, a shell of thin material interposed between said members for transmitting stress from one to the other, said shell having an irregular surface connected with one of said members, and yielding projections on the other of said members for engaging said shell at spaced points thereon while projections thereof intermediate said points are free from supporting contact for distributing stress produced by a load supported by said insulator.
18. An insulator comprising a pair of members having a sheet of resilient material interposed therebetween for transmitting stress from one of said members to the other, said sheet having an irregular surface secured to one of said members by connecting material, and spaced resiliently flexible 70 projections on the other of said members arranged to engage said sheet at different points thereon for distributing stress produced by a load supported by said insulator.
19. An insulator comprising a dielectric member, a pin for said member, a resilient sheet metal shell interposed between said pin and dielectric member for transmitting stress from one to the other, said shell having an irregular surface secured to said dielectric member by cement, and resilient projections on said pin having engagement at their extremities only with said shell at different points thereon for distributing 75 stress produced by a load supported by said insulators.
20. An insulator comprising a supporting member and a dielectric member, resilient projections on said supporting member, and a sheet of yielding material carried by said projections and contacting with said projections only at points spaced from the bases thereof, said dielectric member being connected with said supporting member by said sheet.
21. An insulator comprising a dielectric member, a supporting member, and means for connecting said members comprising a sheet of yielding material having one face 85 thereof connected with said dielectric member and yielding projections carried by said supporting member and arranged to engage the face of said yielding material opposite said dielectric member only at points on 90 said projections spaced from said supporting member.
22. An insulator comprising a supporting member having spaced resilient projections extending therefrom, a sheet of yielding material carried by said projections and having engagement therewith only at points spaced from said supporting member so that said sheet of yielding material is free to give 105 relative to said supporting member at all 110 points on said sheet, a dielectric member, and means for securing said dielectric member with said sheet of yielding material to form connection between said dielectric member and said supporting member.
23. An insulator comprising a metallic member having spaced resiliently flexible projections extending therefrom, an envelope of yielding sheet material supported by the extremities of said projections and clos- 120 125 130

ing the interstices between said projections, a dielectric member, and connecting material for securing said dielectric member to said metallic member, said connecting material engaging said envelope but excluded thereby from said interstices.

24. In an insulator, the combination of a dielectric member and a fitting therefor, said fitting having spaced projections thereon, a cover of sheet material for closing the space between said projections, and connecting material engaging said cover and excluded from said space by said cover.

25. In combination, a dielectric member, a fitting for said member having spaced projections thereon, a sheet metal cover carried by said projections and bridging the space therebetween, and connecting material for securing said fitting to said dielectric member, said material engaging said sheet metal cover and held thereby from entering the spaces between said projections.

In testimony whereof I have signed my name to this specification on this 18th day of August, A. D. 1919.

ARTHUR O. AUSTIN.
